UNITED STATES PATENT OFFICE.

CHARLES STARYSKY, OF MARYSVILLE, TEXAS.

PACKING FOR OIL WELLS.

Application filed January 13, 1927. Serial No. 160,990.

In the present pumping tubing packers the constant weight is required to maintain the packer in expanded position, thus leaving a slack in the tubing which will of necessity cause loosening of the tubing joints by reason of the motion or vibration, thereby giving considerable trouble in the operation of fishing. Furthermore, the pumping rods working in the slack tubing cause wear of the rods and tubing.

It is very often impossible to set a screw packer sufficiently tight to cut off all the water because of the fact that the slack causes binding against the casing at the time of screwing and such packers cannot be released by a reverse screwing and must be directly pulled, thereby causing a breakage in the fishing implements.

It is an object of the present invention to provide a packer which may be readily placed in position and by a simple operation be expanded and locked into place, the packer being readily removed without danger of breaking any of the parts employed in removal.

A further object of the invention is the provision of a packer which may be expanded and fixed in position without requiring a constant weight for maintaining the packer in position so that tension in the tubing may be taken up and thus prevent working loose of the joints in the tubing and also eliminate the wear on the rods and tubing.

A still further object of the invention is the provision of a packer which may be employed at various elevations in a well and having interfitting members adapted to maintain the packing in expanded relation, the interfitted members being readily released by a sufficient pull which will not require such a force as may cause breakage in the pulling elements.

Another object of the invention is the provision of an efficient simple and durable packing which may be employed as a skeleton packer in any relation where slack is intended to be eliminated in joined tubing.

This invention will be best understood from a consideration of the following detailed description, in view of the accompanying drawings forming a part of the specification; nevertheless it is to be understood that the invention is not confined to the disclosure, being susceptible of such changes and modifications which shall define

no material departure from the salient features of the invention as expressed in the appended claims.

In the drawings:

Figure 1 is a vertical section of the lower end of a well casing showing my packing in position before being expanded,

Figure 2 is a vertical section of the lower end of a well casing showing my packing expanded and fixed in position,

Figure 3 is a horizontal section taken along the line 3-3 of Figure 1,

Figure 4 is an enlarged detail view in elevation of my packing,

Figure 5 is a vertical section of my packing after being fixed and expanded, and

Figure 6 is a view in perspective and partly in section of my packing expanded and fixed in position.

Referring more particularly to the drawings 10 designates a customary well casing and in which is mounted a weight joint 11. This weight joint combines the function of connecting the cable, not shown, with the pump plunger 12, and is adapted to expand an oil well packer, generally designated by the numeral 13, within the well casing. The weight joint 11 has a suitable connection with the stem 14 of the plunger 12. The weight joint carries a substantial disc-plate which is capable of being let down upon the lower abutment 15 so that the weight of the weight joint is imposed upon the skeleton joint 16 and so transfers it to the packer 13, the disc-plate being designated by the numeral 17. All of the parts referred to above form no part of the present invention as they have been described and claimed in my co-pending application, S. N. 41,735, filed July 6, 1925.

The packer, designated by the numeral 13, and shown in position in a casing in Figures 1 and 2, consists of a hollow tubular member 18 having corrugations intermediate its ends to provide ribs 19. The upper end of the member 18 has an expansion stop ring 20 formed integrally with the said member and is movable within an expansion chamber 21 formed in the inner wall of the stop 22 of the telescoping member 23. The lower end of the male member 18 is provided with a ring 24 spaced from the stock 25 of said member. The reduced lower end 26 of the stock is provided with external threads 27 and internal threads 28. The threads 27 are adapted to receive the

threads of the next lower connection indicated at 29. The inner threads 28 are adapted to receive the threads on the lower succeeding tubing.

5 The telescopic member 23 has an external flange 30 spaced from a shoulder 31 at the lower end of the stock 22 to provide a space to receive a ring portion 32 of the rubber packing 33. It will be noted that the packing is wired, as shown at 34, and adjacent to the ring portion 32. The upper end of the stock is reduced, as shown at 34^a, and threaded at 35 to receive the threads of the next upper connection. This reduced portion is also internally threaded, at 36, into which is threaded the upper tubular connection.

10 The lower cylindrical portion 37 of the member 23 is provided with a plurality of 20 corrugations to receive the ribs 19 of the member 18. The cylindrical portion 37 has a plurality of slits 38 running longitudinally of said portion to provide resilient fingers 39 which are adapted to be forced over the 25 ribs 19 for a purpose which will be presently explained. These fingers at their lower free ends are tapered at 40 adapted to be received within the tapered seat 41 of the expandable packing 33. The member 23 may be 30 formed of any suitable metal, but the metal must be of such a character that the fingers 39 will be resilient so that they may be expanded when being moved over the annular ribs 19 when the member 23 is forced into 35 telescoping relation with the member 18.

40 The packing 33 has at its lower end an internal groove 42 adapted to receive the annular flange 24 on the member 18 and a portion 43 of the packing is adapted to be received between the flange 24 and a shoulder 44 formed on the upper end of the stock 25 of the member 18. The inner circular portion of the ring 43 of the packing 33 embraces the cylindrical portion 45 of the 45 member 18. This portion 23 is directly opposite the wired section 46 at the lower end of the packing 33. The inner wall of the packing 33 is cylindrically shaped generally throughout its length except the lower end, 50 as shown at 47, which is enlarged to neatly engage the cylindrical portion 48 of the member 18.

55 The application of my device is as follows: The packing including the telescoping members 18 and 23 and the expandable packing 33 are properly co-ordinated so that they will appear in the positions shown in Fig. 1. The packing is then let down at the proper position and sufficient weight is

60 applied to the stock 22 of the telescoping member 23, forcing the stock downwardly and likewise the telescoping member 23 with the fingers 39 riding over the ribs 19 of the member 18 until the corrugations in the fingers neatly fit the ribs 19 of the member 65 18 whence the members 18 and 23 are locked together against movement. At this time the shoulder at the lower end of the stock 22 acts upon the upper end of the packing 33, compressing said packing and causing the 70 same to expand and snugly engage the inner wall of the casing 10. As has been stated the fingers 39 are resilient and, therefore, will easily ride over the ribs 19 until the corresponding corrugations and ribs of 75 the two members will be interfitted. It must be borne in mind that the stock 25 of the male member 18 is maintained against movement during the compressing of the expandable packing 33.

80 In case the packer is employed as a top packer a set collar may be used to withdraw tubing. In any case, where the packer is removed, a sufficient pull on the packer will release the female member 23 from the male member 18 so that the compression in the packing or sleeve 33 will be relieved and the packer may then be withdrawn.

85 I claim:—

90 A packing comprising a cylindrical member having an enlarged portion provided with a chamber, a second cylindrical member received within the first member and having a stop ring movable in said chamber for limiting the movement of the first mentioned member relative to the second member, 95 each of said members has cooperating corrugations and ribs for locking the members together when the first mentioned member is moved relative to the second member, the first member having spring fingers carrying said ribs for facilitating the locking of the sections together; a shoulder carried by each member and an expandable and contractible sleeve embracing the members and having an end in engagement with a shoulder of the member, said spring fingers being located between the opposite ends of the sleeve, said sleeve being adapted to be compressed when the members are moved into 100 locking relation with each other, the opposite ends of the expandable and contractible sleeve being provided with an annular groove and a rib on each cylindrical member adapted to be received within a groove of the 105 sleeve.

CHARLES STARYSKY.
